UNITED STATES PATENT OFFICE.

WILLOUGHBY C. NELSON, OF OMAHA, NEBRASKA, ASSIGNOR OF ONE-HALF TO
C. W. CONKLING, OF TEKAMAH, NEBRASKA.

CAMP-STOVE.

1,276,795.

Specification of Letters Patent. Patented Aug. 27, 1918.

Application filed February 20, 1918. Serial No. 218,322.

To all whom it may concern:

Be it known that I, WILLOUGHBY C. NELSON, a citizen of the United States, residing at Omaha, in the county of Douglas and 5 State of Nebraska, have invented certain new and useful Improvements in Camp-Stoves, of which the following is a specification.

This invention relates to an improvement 10 in camp stoves, and has for one of its objects to provide such a construction that the stove and liquid fuel, together with operating parts, may be contained in a portable receptacle, and so arranged that the device will 15 be convenient in use. Other objects relate to means found to be of advantage for generating gas and mixing it with air so that a required maximum degree of heat may be produced with a minimum quantity of 20 liquid fuel. Also to provide a complete gas stove by use of few and simple parts so that manufacture may be economical and practical and that durability may be attained.

25 With the foregoing objects in view and others to be mentioned hereinafter, the invention presents a novel construction, combination and arrangement of parts as described herein and claimed, and as illustrated in the accompanying drawing, wherein,—

Figure 1 is a perspective view of the device, the cover and grate being elevated. Fig. 2 is a plan view of the primer, gas 35 burner and gas generator, the control rod for the gas feed being in section. Fig. 3 is a view of the stove in longitudinal section, a part of the receptacle being also shown, with the lid and grate lowered. Fig. 4 is a trans- 40 verse section on line 4—4 of Fig. 3. Fig. 5 is a broken away detail relating to Fig. 2.

Referring now to the drawing for a more particular description, I provide a receptacle *x*, preferably rectangular in plan, having 45 an upright partition *6* near its rear end and a lid *7*. A grate is indicated at *7'* and, preferably, it is supported upon a ledge *8*, this ledge being disposed near the top of the receptacle, the vertical flange *a* of the 50 ledge being suitably secured to the upright partition, the grate preferably being formed by use of a metallic rod bent to provide a plurality of loops disposed in a single plane and having its ends bent outwardly for en- 55 gaging in the socket members *9*, which are

secured to said ledge, so that the grate may have swinging movements in an arc of a half circle or at least of 90 degrees, a ledge 10 being provided and having a flange *b* secured to the front end of the receptacle, 60 so that the grate may be adequately supported when disposed in a horizontal position, for holding cooking utensils.

The stove consists, in part, of a casting 11 provided near its top with a gas chamber 65 12 preferably of disk form in plan, said casting being provided with a foraminous cap *c* which is formed concavo-convex at its middle to provide a channel 13 opening on its upper face. The casting is also provided, below the gas chamber, with a mixing-chamber 14, and with a recess 15, open at its top, to operate as a priming-pan, said recess being disposed in a plane below chamber 12 and forwardly of chamber 14. 70

Numeral 16 indicates an air intake port for the chamber 14, said port being near the priming-pan and under control of a valve 17; and by means of a port 18 the chamber 14 communicates with chamber 12, said last 80 named port being comparatively remote from the air intake port 16.

A second mixing-chamber 19 is provided, this being disposed below the gas chamber 12 and below a disk 20, said disk being provided with apertures *d* and being mounted upon an annular ledge or ridge 21, said ridge preferably being a part of the casting 11 and providing a threaded connection for the cap or burner *c*, the apertures of the 90 disk being comparatively remote from the port 18. Suitable legs 22 are provided for the casting 11, and are secured to the bottom of the receptacle.

An imperforate, tubular gas generator is 95 indicated at 23 having a length in excess of the diameter of the gas chamber. It is disposed within and substantially fills the channel 13 and, subject to a strainer 24, is in communication with a conduit 25 for liquid 100 fuel, said conduit traversing the upright partition 6 for conducting liquid fuel from the tank 26, subject to the control of a valve *h*, said tank being provided with a suitable air valve 27, so that by use of a conventional 105 air pump (not shown) the liquid may be conducted, as may be required, to the generator 23, by air pressure.

The front end portion of the gas generator 23 projects downwardly and is provided 110

- at its terminal with a gas container 28 formed circular in plan and elliptical in cross-section, said container being disposed above, with its longitudinal axis in line with 5 the axis of the recess 15, and having a nozzle 29 traversing the upright wall *e* of the casting, the discharge orifice *f* of the nozzle being disposed in the mixing-chamber 14, immediately above the air intake 16.
- 10 The needle 30 for controlling the orifice of the nozzle has bearings in a projection 31 with which the wall of the gas container 28 is provided, and its longitudinal reciprocation may be under any suitable manual 15 control, the means herein shown being an upright, revoluble shaft or rod 32, its lower end being mounted in a projection *g* which is disposed below and extends forwardly of the projection 31, the rod 32 being provided 20 with a projection or finger 33, best shown in Fig. 5, engaging in a notch 34 which is formed in the flat portion 35 with which the needle is provided.

Numeral 36 indicates a vertical slot 25 formed in the wall *e* of the casting, in communication with the chambers 19 and 12, and a plurality of passageways 37 are provided which communicate with the slot and the recess 15, closely adjacent to and below 30 the nozzle 29.

Among some of the advantages to be derived by use of the invention, it may be stated that the device is readily portable, the lid 7 being hingeably mounted and provided with fastening devices, as shown in the drawing, the disk 20 forming a partition between the second mixing-chamber 19 and the gas chamber 12, being removably secured upon the seat 21 by means of suitable keepers *h*. On account of the provision of the slot 36 and passageways 37, combustion of gas will occur and will be maintained in proximity to that part of the nozzle 29 within the recess 15, to facilitate generation of gas. By use of the rotatable control-rod 32, an adjustment may be made for a supply of gas from the container 26 to the mixing-chamber 14, the rod 30 having bearings in the projection 31 so that it will be 45 maintained in line with the orifice *f* of the nozzle. It will be appreciated that the channel 13 is of advantage for a mounting therein of the gas generator 23, since this 50 feature facilitates maintainance of a required degree of heat, after ignition occurs at the cap *e* of the burner.

In operation, the valve *h* being opened, a supply of liquid fuel, under pressure, will enter the gas generator 23 by passing the 60 strainer 24. The operator, as usual, ignites a small quantity of liquid fuel in the priming-pan for generating the gas, this heat being depended upon for that purpose until a normal degree of heat has been attained 65 for other metallic parts. It is considered

that as described, the parts are arranged to advantage for permitting the heat to be communicated to the container 28 and tube 23, for generating the gas.

Upon passing the orifice *f*, the gas will be 70 come readily mixed with air, since the port 16 is disposed below said orifice, and the fuel mixture, after passing the port 18 to the chamber 19, will become more thoroughly mixed than before, since the apertured disk 75 20 operates as a baffle-plate.

After an operator causes the fuel mixture to be ignited at the interstices of the burner-cap *e*, the gas will thereafter be generated in the tube 23, independently of any liquid 80 fuel in the priming-pan 15. However, ignition of gas supplied by the passageways 37 will continue, this feature being of great advantage for maintaining a desired degree of heat for the nozzle 29. It will be understood, of course, that the wall *e* of the casting will attain a high degree of heat, during operation, this being an advantage for causing the gas to become heated while moving to the discharge passageways 37. During 85 operation, the greatest degree of heat, of course, will occur at the upper and front parts of the stove, and this feature facilitates the movement of air through the port 16 and mixing chambers, said air supply 90 moving from the lower and rear parts of the stove to enter the mixing chambers. If the supply of air causes a mixture less rich in hydrocarbons than desired, admission of air may be controlled by means of the 95 valve 17.

While I have explained details of construction, I do not wish to be understood as limiting myself to exactness in this respect, and I may make changes in minor details as 100 well as changes in form size and proportion of parts as may be found to be of advantage, the scope of the invention being determined by the appended claims.

I claim,

1. A stove, comprising, in combination with a casting providing a priming receptacle and a mixing chamber having an air intake, and provided with a ridge above the mixing chamber, an apertured partition 115 mounted on the ridge providing a second mixing chamber in communication with the first named mixing chamber, a foraminous cap above the second mixing chamber, said cap being provided with a groove and 120 mounted on the casting, a tubular member for receiving liquid fuel disposed in the groove of the foraminous cap, a container in communication with the tubular member, said container being disposed above the 125 priming receptacle and having a discharge port communicating with the first named mixing chamber, and means movable within the container for controlling the discharge port thereof.

2. In a camp stove, a casting providing a priming receptacle, a gas chamber with a grooved, foraminous wall, and a mixing chamber below and in communication with the gas chamber, a tubular member for receiving a liquid fuel engaging the grooved wall of said gas chamber, a container for receiving gas from the tubular member and having a nozzle projecting within the mixing chamber, a needle movable in said nozzle, said casting being provided with passageways communicating with the gas chamber and priming receptacle, and also being provided with an air intake port communicating with said mixing chamber.

3. In a camp stove, the combination with a casting having a mixing chamber with an air intake and provided with a ridge above said mixing chamber, an apertured disk on said ridge to provide a second mixing chamber in communication with the first named mixing chamber, a liquid fuel tank, a gas chamber having an annular wall threaded on said ridge and having a foraminous top with a channel formed therein, a tubular member engaging in said channel in communication with the gas tank, a gas container communicating with the tubular member and having a discharge port communicating with the first named mixing chamber, means for controlling the discharge port of said gas container, and means for applying heat to said gas container.

4. In a camp stove, a casting providing an upper chamber having an upper foraminous wall with a channel formed therein to open on its top, and providing a lower chamber having an air intake port in its bottom and a port communicating with the upper chamber, and providing a priming receptacle disposed in a plane below the upper chamber outwardly of the lower chamber, a tank for liquid fuel, a tubular member having a conduit communicating with the tank and disposed to substantially fill said channel, a container disposed above the priming receptacle in communication with the tubular member and having a discharge nozzle normally communicating with said lower chamber, a foraminous partition between the upper foraminous wall and bottom of the upper chamber, and a needle adapted to be reciprocated longitudinally for closing the orifice of the nozzle, said casting being provided with a passageway in communication with the priming receptacle and in communication with that part of the upper chamber below said foraminous partition.

In testimony whereof I have affixed my signature in presence of two witnesses.

WILLOUGHBY C. NELSON.
